UNITED STATES PATENT OFFICE.

JEROME F. HEYN, OF OMAHA, NEBRASKA.

AIR FILTER.

Application filed December 8, 1924. Serial No. 754,821.

To all whom it may concern:

Be it known that I, JEROME F. HEYN, a citizen of the United States, residing at Omaha, in the county of Douglas and State 5 of Nebraska, have invented certain new and useful Improvements in Air Filters, of which the following is a specification.

My invention relates to filtering devices of the class suited for removing dust and 10 particles of solid matter from air passed through the same. It is the object of my invention to provide a filter of this class especially adapted for use with the engines of motor vehicles, to prevent the introduction 15 of dust and abrasive material with the air drawn into the engine through the carbureter. A further object is to provide a device of this character with which the filtered air supplied to the carbureter may be pre-heated. A further object is to provide an 20 air filter in which the filter as a whole is formed by a series of similar units, whereby the filter-area desired may be secured by the assembling of a suitable number of the units, 25 and whereby a defective or damaged portion of the filter may be replaced without renewal of the entire filter. A further object is to provide, for filter-units of the character above mentioned, a casing of such construction 30 that its capacity may be readily adapted to various numbers of the units. Further objects of my invention relate to the particular construction of the filter-units, and to the means for retaining them in operative 35 combination with the casing, and will be more fully set forth hereinafter.

In the accompanying drawings Fig. 1 is a side elevation of a motor-vehicle engine equipped with an air-filter embodying my 40 invention, Fig. 2 is a longitudinal section of the filter, some of the units being in elevation, Figs. 3, 4 and 5 are transverse sections taken, respectively, on the lines 3—3, 4—4 and 5—5 of Fig. 2, Fig. 6 is a detail axial 45 section of one of the filter-units, and Fig. 7 is a partial section of one end of the casing, showing the arrangement of the packing which prevents leakage past the filter-units from the intake to the outlet compartments.

50 In carrying out my invention I preferably employ for the filtering medium a strong

close-woven fabric, such as is commonly used for the dust-collecting bags of vacuum-cleaners. The filter-units hereinbefore mentioned are each formed by a section of the 55 fabric having its edge portions secured to a rigid metal frame, so as to be held taut across one side of the frame. For greatest convenience of construction the metal frames are circular, and each frame comprises a 60 pair of rings having interengaged marginal flanges between which the fabric is clamped. Referring to Fig. 6, the first frame-ring has a body-portion 10 which is substantially flat at the inner portion but is slightly dished 65 near its outer edge, and has a marginal flange 12 turned in toward the concave side of the dished portion. The fabric 11 is stretched over the face of the body-portion 10 at the side thereof which has the convex 70 margin, the fabric being carried about the flange 12 to the inner side thereof. The second frame-ring has a short cylindrical body-portion 14, with a narrow inturned flange 15 at one end, and an out-turned 75 flange 16 at the other end, the latter flange fitting within the flange 12 of the first ring, and the marginal portion 17 of the fabric being clamped between said flanges 12 and 16. The frame-rings and fabric may be 80 conveniently assembled by the use of suitable dies such as are employed for the manufacture of covered buttons, and of which the construction and use are well known. It is noted that the inward swaging of the 85 ring-flange 12 which effects the clamping of the fabric edges between the rings, also draws the central portions of the fabric taut, so that the same extends across the open central portion of the ring 10 like a tympanum or diaphragm.

In the assemblage comprising the frame-rings and fabric, the portions which project laterally beyond the cylindrical body-portion 14 of the second ring form a rim or 95 annular bead, and at diametrically opposite points this projecting rim or bead is indented or swaged inwardly, to form two rounded depressions or grooves 18 which at their centers extend only slightly outside the ring-portion 14, being offset therefrom by merely the thickness of the fabric and of the

metal in the flange 12. In one half of the ring-body 14, circumferentially intermediate the grooves 18 of the projecting rim, are formed a series of slots 19.

5 In the construction of my filter I place together a series of the described filter-units, the several units being disposed coaxially, with the face or fabric-covered side of one unit pressed against the back of the next, 10 so that the inturned flange 15 of each unit engages the fabric of the next, and said fabric serves as a gasket to prevent leakage radially between the successive frames. In the assemblage of units the grooves 18 15 are aligned longitudinally with each other, and the alternate units are reversed as to the position of the slots 19, so that in half of the units of the series the slots are at the lower side, and in the intervening units 20 the slots are at the upper side. The units are held in their assembled relation by means of a clamping-frame, comprising rings 20 and 21, and a pair of longitudinally extending rods 22 which are threaded at 25 their extremities and provided with nuts 23 for engaging the rings 20 and 21 to press them toward each other. The clamp-rods 22 are so disposed as to extend parallel with the series of grooves 18 in the edges of the filter-units, but are spaced laterally from 30 said grooves, as best shown in Fig. 5. Upon the clamp-rods between the end-rings 20 and 21 are disposed cylindrical packing-members comprising series of washers 24 35 of felt or like compressible material, the diameters of said packing-members being such that they are pressed into the grooves 18 and against the sides of the ring-portions 14 intermediate said grooves, whereby 40 to be in contact with the series of filter-units along continuous longitudinal lines. The compressible packing material, by yielding longitudinally of the clamp-rods, permits the variations of distance between the 45 clamp-rings 20 and 21 needed to compensate for the longitudinal compression of the series of filter-units when the same are clamped together, at the same time preserving a dust-tight joint with the lateral edges of the units. The central opening 50 through each of the rings 20 and 21 is of substantially the same diameter as the openings through the frame-rings 10 of the filter-units. In the edge of each of the clamp-rings 20 and 21 there is a rectangular groove 55 which extends peripherally of the ring between points adjacent to the openings for the clamp-rods. At the opposite edge, or between the ends of the peripherally grooved portion, the ring is reduced or cut away 60 to a radius substantially the same as that of the outer portions of the filter-units. In the said peripheral groove is disposed a strip 25 of compressible packing material, 65 such as felt, the normal transverse section

of the strip being such that when it is forced into the groove it will tend to bulge therefrom at the open outer side of the groove. Adjacent to the clamp-rods, the side or face of the ring adjoining the packing-washers 24 has a notch or recess 26, shown in Figs. 5 and 7, so that said washers may engage the side of the packing-strip 25, as indicated clearly in the latter figure. The grooved portions of the rings 20 and 21, containing the packing-strips 25, are disposed respectively at the lower and upper sides of the assembled series of units.

The assemblage of units, together with the clamping means and packing members, is disposed within a cylindrical casing 27 having a diameter such that the packing material 24 and 25 is in contact therewith along a continuous line extending about the lower edge of the ring 20, thence longitudinally 70 parallel with the clamp-rods to the ring 21, and thence about the upper edge of said ring 21. The packing thus separates the space within the casing into two compartments 28 and 29, the first including the space 75 at the outer face of the ring 21 and about the lower side of the filter-units, and the other compartment including the space above the filter-units and at the outer face of the ring 20. The casing-cylinder 27 is 80 provided with heads 30 each having an inwardly extending flange 31 fitting about the adjacent end of the cylinder, and having perforate lugs 32 which are employed for connecting the casing with a support. The end-portions of the clamp-rods 22 are extended 85 through the casing-heads 30, and nuts 33 are screwed upon the threaded terminals of said rods to hold the heads in place. Tubular bosses 34, formed integrally with the heads 30, enable the casing to be connected with 90 suitable pipes or conduits for supplying air to the compartment 28, and for drawing air from the compartment 29. It will be clearly apparent from Fig. 2 that air from the 95 compartment 28 may pass through the slots 19 of those filter-units in which said slots are at the lower side, thus entering the spaces or intake chambers between alternate pairs 100 of the fabric tympani, and by passing through the filter-fabric enter the other spaces or outlet-chambers from which the slots 19 at the upper sides provide egress to the casing outlet-chamber 29.

At the lower side of the casing-cylinder 110 27 are a plurality of openings 35, and beneath said openings is disposed the pan 36. At the longitudinal edges of the pan are out-turned flanges 37 which fit upon and are held against the cylinder 27 by means of 115 nuts 38 engaging the outer portions of screws 39 attached to and extending outwardly from the casing. Dust received in the intake-chambers of the filter-units, and falling therefrom through the slots 19 to the 120 130

lower side of the casing, passes through the openings 35 and is received in the removable pan, which may be taken off and the accumulated material shaken out of the pan.

5 A typical use of my air-filter, for preventing the introduction of dust with the charge supplied to an internal combustion engine, is represented in Fig. 1. The filter-casing is mounted by means of suitable brackets or 10 supports 40 connected with the lugs 32 on the heads 30. The tubular boss on the head adjoining the compartment 29 is connected with the air-intake pipe 41 of the engine carbureter, and to the opposite end of the 15 filter-casing is connected the flexible tube 42 which extends to the air-heater 43. Unheated air may be supplied to the filter intake if desired, and when connection is made with the air-heater as shown, it is not essential 20 that the connections be tight, as any leakage between the heater and casing will result merely in a slight lowering of the air temperature. Leakage of the connections between the filter-casing and the carbureter 25 should be carefully prevented, however, as the same would permit unfiltered or dust-laden air to be mixed with the charge and drawn into the engine cylinders.

It will be seen that my invention provides 30 an efficient and inexpensively constructed means for filtering or removing dust from air, in any situation where it is desirable that a considerable volume of air be supplied, substantially free from suspended particles of solid matter. By the described structure, a large filter-area may be provided in a relatively small space, and the greater portion of the solid material which accumulates in the filter may be readily removed 35 by slightly jarring the device to cause the material to be shaken down into the removable pan. The structural alterations required to vary the filter-area, in adapting the device to particular requirements, involve 40 merely the increasing or decreasing of the number of the filter-units assembled, and the provision of longer or shorter clamp-rods and a longer or shorter cylinder for the 45 casing.

50 Now, having described my invention, what I claim and desire to secure by Letters Patent is:

1. In a structure of the class described, an annular frame comprising a pair of rings 55 having interengaged flanges, a fabric covering extending across the face and about the edges of one of said frame-rings and having its edges clamped between the inter-engaged flanges of the rings, the other ring having a laterally perforate portion, and an in-turned flange on the latter ring at the end opposite the fabric-covered face of the first ring.

2. In a structure of the class described, a 60 series of filter-units each comprising an an-

nular frame and a fabric covering extending across one face of the frame, each frame having a laterally perforate portion, said perforate frame-portions of successive units being at opposite sides of the series, means for 70 clamping the series of units together longitudinally, a casing inclosing the units and clamping means, and packing means extending continuously between the casing and the series of units along longitudinal lines 75 intermediate the perforate frame-portions and about opposite sides of the series at the ends thereof.

3. In a device of the class described, a series of filter-units each comprising a cylindrical frame having radial openings in one side and a fabric covering stretched across one end thereof, said series of units arranged coaxially and with the open end of each engaging the fabric-covered end of the next, the radial openings of the frames being at alternate sides of the successive units, clamp-rings disposed at the ends of the series of units, clamp-rods extending between said rings and laterally spaced from the filter-units, longitudinal packing means disposed about said clamp-rods and engaging the adjacent sides of the filter-units, a cylindrical casing disposed about the clamping means 80 and engaging said longitudinal packing 85 means, and circumferential packing means extending about laterally opposite sides of the clamp-rings intermediate the ends of the longitudinal packing means.

4. In a structure of the class described, a filter-unit comprising a metal ring having a flat body-portion and an inturned marginal flange, a sheet of fabric extending across the central opening of said ring and about said flange, and a second ring having a cylindrical body-portion and an out-turned flange at one end of said body-portion, said flange coacting with the inturned flange of the first ring to clamp the edge portions of the fabric between them, said flanges being indented at diametrically opposite sides into substantial alinement with the cylindrical body-portion of the second ring, and said body-portion being perforate at one side circumferentially intermediate the flange indentations.

5. In a device of the class described, a tubular frame structure, a series of fabric tympani extending transversely of said tubular frame and dividing the same longitudinally into a plurality of chambers, and inclosing means forming intake and outlet compartments at opposite sides of the tubular frame, there being openings through the sides of the tubular frame connecting the alternate chambers between the fabric tympani with said intake and outlet compartments.

6. Air-filtering means comprising a series of fabric tympani disposed in parallel 130

spaced relation, a tubular frame structure supporting said series of tympani and laterally inclosing a series of chambers between them, a casing disposed about said tubular frame and connecting therewith to form intake and outlet compartments at opposite sides thereof, the tubular frame having lateral openings connecting the successive chambers between the tympani alternately with said intake and outlet compartments, 10 and means for connecting supply and discharge conduits with said intake and outlet compartments.

JEROME F. HEYN.
